[57] CLAIM

The ornamental design for a combined book mark and template, as shown and described.

DESCRIPTION

FIG. 1 is a front elevational view of a combined book-mark and template showing my new design;

FIG. 2 is a side elevational view, the opposite side being a mirror image thereof; and

FIG. 3 is an end elevational view, the opposite end being a mirror image thereof.

Fig. 1.Fig. 2.*Fig. 3.
